UNITED STATES PATENT OFFICE

114,765

DESIGN FOR A DISPLAY BAG

Anthony Palmigiano, Jr., Brooklyn, N. Y.

Application August 1, 1938, Serial No. 79,015

Term of patent 3½ years

To all whom it may concern:

Be it known that I, Anthony Palmigiano, Jr., a citizen of the United States, residing at Brooklyn, in the county of Kings and State of New York, have invented a new, original, and ornamental Design for a Display Bag, of which the following is a specification, reference being had to the accompanying drawing, forming a part thereof.

The figure is a perspective view of a display bag showing my new design, the opposite side of the bag being plain.

I claim:

The ornamental design for a display bag, as shown and described.

ANTHONY PALMIGIANO, JR.
